CLAIM

The ornamental design for an escutcheon for a bathroom fitting, as shown and described.

DESCRIPTION

FIG. 1 is a perspective view taken from the top, front and left side of an escutcheon embodying my new design;

FIG. 2 is a left side elevational view thereof, the right side being a mirror image of the left side;

FIG. 3 is a top plan view thereof, the bottom being the same as the top;

FIG. 4 is a front elevational view thereof; and,

FIG. 5 is a rear elevational view thereof.

FIG.1

FIG. 2

FIG. 3

FIG. 4

FIG. 5
